RAILWAY CENTRALIZED TRAFFIC
CONTROLLING APPARATUS

Arthur L. Jerome, Edgewood, Pa., assignor to The
Union Switch & Signal Company, Swissvale,
Pa., a corporation of Pennsylvania

Application July 16, 1945, Serial No. 605,284

11 Claims. (Cl. 246—3)

1

My invention relates to railway traffic controlling apparatus and particularly to improved circuits for use in centralized traffic control machines for remote control of traffic in track stretches in which traffic may move in either direction.

In application for Letters Patent of the United States, Serial No. 567,188, filed December 8, 1944, by Frank T. Pascoe and Arthur L. Jerome, which issued as Patent No. 2,411,387, November 19, 1946, there are shown interlocked circuits at the control office governed by the signal control levers which govern train movements into the opposite ends of a track stretch, so as to prevent interference with train movements in the event of improper manipulation of these levers and to prevent the reversal of the direction of traffic except when the single track stretch is unoccupied and the signals governing entrance of traffic into the stretch are at stop.

An object of my invention is to provide an improved system of the type described, but which requires less apparatus than the system of the application identified above.

A further object of the invention is to provide a system of the type described which employs an auxiliary relay which is operated in response to a change in the position of the master directional relay and which remains in its operated position until an indication code is received showing that traffic in the associated track stretch has been established in the direction designated by said master directional relay.

Another object of the invention is to provide a system of the type described in which the auxiliary relay, when operated, establishes circuits to energize the starting relays for transmitting control codes to the field stations at both ends of the associated stretch when the starting button for the station at either end of the stretch is pressed.

A further object of the invention is to provide a system of the type described in which the auxiliary relay, when operated, removes the master directional relay from the control of the block indication relays, and which when operated cancels the existing block indications.

Another object of the invention is to provide an improved system of the type described in which the auxiliary relay controls the circuits of the block and directional indication lamps on the panel of the C. T. C. machine to prevent improper lighting of these lamps during a change in the direction of traffic in the associated stretch.

A further object of the invention is to provide an improved system of the type described which

2

is arranged to insure that the auxiliary relay returns to its normal position if, following a change in the direction of traffic in a track stretch, a train enters the stretch before an indication is transmitted to the office that the stretch has been prepared for the new direction of traffic.

Another object of the invention is to provide an improved system of the type described.

Other objects of the invention and features of 10 novelty will be apparent from the following description taken in connection with the accompanying drawings.

I shall describe one form of railway signaling 15 system embodying my invention and shall then point out the novel features thereof in claims.

In the drawings,

Figs. 1A and 1B when placed together with Fig. 1A at the left, form a diagram of a stretch of single track railway equipped with wayside signaling apparatus governed by a centralized traffic control system, and

Fig. 2 is a diagram of a portion of the control machine at the office.

In practicing my invention I provide in the 25 C. T. C. machine a normally released auxiliary relay for each track stretch and control it by the master directional relay and by the block and detector section indication relays for the stretch.

On movement of the contacts of the master directional relay a pick-up circuit is established for the auxiliary relay over a front contact of a block indication relay. When the contacts of the auxiliary relay move to their operated or picked-up

35 position, the auxiliary relay releases or operates the block indication relay and establishes for itself one or the other of two stick circuits governed by the block indication relays and by the master directional relay depending on the position of the contacts of the master directional relay, while the effective stick circuit is interrupted on receipt of an indication code which picks up the block indication relay which corresponds with the position of the master directional relay.

40 In addition, the circuit of the auxiliary relay is governed by the detector section indication relays to insure that the auxiliary relay releases or is restored to normal when a train enters the stretch. The auxiliary relay when operated or picked up establishes a circuit to permit operation of the master directional relay even though the block indication relays are released, while the auxiliary relay, when picked up, interrupts the circuits of the block and directional indication lamps to prevent improper lighting of these

45 50 55

lamps during a change in the direction of traffic in a stretch.

Referring to Fig. 1 of the drawings there is shown therein a stretch of single track railway extending between two passing sidings and provided with wayside signal apparatus for authorizing traffic to move in one direction through the stretch at times and to move in the other direction at other times. In this application only the portions of the wayside apparatus essential to the understanding of this invention have been shown and the remainder of the equipment may be arranged as shown in application for Letters Patent of the United States Serial No. 501,254 of H. S. Young, filed September 4, 1943.

As shown, the wayside signals are of the well-known searchlight type and may be constructed as shown in Letters Patent of the United States No. 1,864,224 issued June 21, 1932, to W. B. Wells.

The equipment at the left-hand or west end of the stretch includes a C. T. C. system field station unit designated station 1-2, and the equipment at the right-hand or east end of the stretch includes a C. T. C. system field station unit designated station 3-4.

The field stations are connected with the office over a pair of line wires, not shown, by a code communication system which may be of the type shown in Letters Patent of the United States No. 2,229,249, issued January 21, 1941, to L. V. Lewis, or in application for Letters Patent of the United States Serial No. 496,907, filed July 31, 1943, by A. P. Jackel, which issued as Pat. No. 2,411,375, November 19, 1946, and described in Manual 506A of The Union Switch and Signal Company, Swissvale, Pa.

Consideration of the detailed mode of operation of the code communication system is not needed for an understanding of this invention and it is deemed sufficient to point out that a field station is provided at each end of each track stretch to be controlled and that coding units are provided at the office and at each field station and are connected by a pair of line wires, not shown, over which control codes are transmitted at times from the office to a selected field station, and at other times indication codes are transmitted over the same line wires from the different field stations to the office without interference. Transmission of each code includes the temporary establishment of a plurality of communication channels, such, for example, as seven between the office and a station to position a group of relays.

Each code includes a distinctive code call by means of which a selector relay 1-2S or 3-4S at the office and a similar relay, not shown, at one station only is energized to effect temporary establishment of seven communication channels between the office and the station. The different stations have different code calls, consequently the selector relays for different stations or panels are not energized at the same time, and the same channels provide communication at different times with all of the stations.

The explanation of this invention requires only three channels employed in the transmission of control codes and five channels employed in the transmission of indication codes, and in order to simplify the disclosure the other channels and related apparatus have not been shown.

In order to simplify Fig. 2 of the drawings, the terminal representing control or indication channels on the office C. T. C. machine which is employed in connection with the field stations

at both ends of the track stretch is in some instances shown as separate terminals for the two field stations, and in other instances is shown as a common terminal for both field stations. However, it should be understood that there is but one terminal on the C. T. C. machine for each control or indication channel, and that these terminals serve all of the field stations. The office machine operates to connect to these terminals the office equipment for the various field stations, but to connect only one station at one time.

The channels employed in the transmission of control codes are designated 2, 5 and 7, and the channels employed in the transmission of indication codes are designated 10, 12, 13, 14 and 15, the numbers employed to designate these channels being the same as are employed to designate the corresponding channels in the above-identified application of H. S. Young.

It is to be understood that the system of this invention is made up of a number of unit portions generally similar to the one shown in the drawings, but as the invention may be fully understood from one such portion, only one has been illustrated in the drawings.

The office and field stations are each provided with a suitable source of direct current, not shown, the terminals of which are designated B and C in the drawings.

In most instances in the drawings the relay contacts are located directly in line with the winding of the relay, but in some cases in order to simplify the drawings, relay contacts are separated from the relay winding and in these instances the relay with which the contacts are associated is designated by appropriate reference characters placed above the contacts.

The equipment at each field station includes a starting relay FST, which responds to a change in position of any of the associated indicating relays to provide connection from terminal B of a source of current to the indication channels to effect delivery of indication codes over the line wires during the time that a delivery relay D at the office is energized to thereby position a group of indication relays in accordance with the condition of energization of the indication channels.

The means for controlling the field station starting relays FST is shown diagrammatically and these relays are controlled as explained in detail in the above-identified application of A. P. Jackel. The field station starting relays are of the polarized type and each has contacts which normally occupy their left-hand or normal position from which they are moved to their right-hand or reverse position to initiate transmission of an indication code. The starting relay contacts are restored to their left-hand or normal position in consequence of the transmission of an indication code by the associated field station.

The indication relays at the office governed from the field station 1-2, at the left-hand or west end of the single track stretch, include a relay 1TK which controls a lamp in the track diagram of the control machine to indicate the condition of occupancy of section 1T, containing the track switch 1W, the relay 1TK being controlled by the track relay 1TR for the track section; a signal indication relay 2RRGP governed by the relay 2RRGP which repeats the stop indication of the signals 2RA and 2RB; and a block indication relay 2RBK controlled by the relay 2RBP which is governed by traffic conditions in the stretch.

The relays at the field station 3—4 at the right-hand end of the single track stretch function in a similar manner to control the relays 3TK, 4LHK and 4LBK at the office.

The block indication lamp BKE in the track diagram of the control machine is governed by the relays 2RBK and 4LBK, one of which at times indicates the condition of occupancy of the single track stretch, and the other of which at other times indicates the condition of occupancy of the single track stretch.

The signal levers 2SIG and 4SIG on the panel of the control machine are the usual three-position levers for the code control of the signal control relays at the field stations at the opposite ends of the stretch. The signal levers 2SIG and 4SIG are electrically interlocked with respect to the control of train movements into the intervening single track stretch by electroresponsive means in the form of the master directional polarized relay 2—4LP, as in the above identified application of H. S. Young and also in his Letters Patent of the United States No. 2,326,991.

The relay 2—4LP has associated therewith the normally released auxiliary relay 2—4LPSR which is provided by this invention and is controlled in the manner explained below.

The push buttons 1—2STB and 3—4STB are the starting buttons for operating the usual code starting relays 1—2ST and 3—4ST by means of which control codes are initiated and the corresponding stations selected. Each starting relay, when actuated or energized, initiates a control code as described in Lewis Patent No. 2,229,249 including a code call for energizing the selector relay S for the same panel. Each selector relay, when energized, releases or restores to normal the associated starting relay and connects terminal B of a local source of energy to selected ones of the control channels in accordance with the positions of the signal levers and of contacts of the master directional relay 2—4LP.

The equipment is arranged so that when energy is applied to channel 2 and a control code is transmitted to a field station the contacts of the traffic directional relay FS at that station are operated to their normal position to condition the wayside apparatus to make that end of the stretch an exit or leaving end. Similarly, the equipment is arranged so that, when energy is not applied to channel 2 and a control code is transmitted to a field station, the contacts of the traffic direction control relay FS are operated to their reverse position to condition the wayside apparatus to make that end of the stretch an entrance end so that the signal at that point may be controlled by the wayside circuits on operation of the associated signal relay.

The equipment is also arranged so that, when energy is supplied to the code channel governing a signal control relay, such as, for example, channel 5 or 7, and a control code is transmitted to a field station, the signal control relay at that station is operated to render the signal subject to the control of the wayside circuits. When energy is not supplied to the code channel governing a signal control relay, and a control code is transmitted to a field station, the signal control relay at that station is operated to keep the signal at stop irrespective of the wayside circuits.

The signal levers 2SIG and 4SIG are of the three-position type and each has a normal center position N, a left-hand position L, and a right-hand position R. These levers control contacts which are shown diagrammatically in the draw-

ings, the contacts which are closed in the left-hand position of the lever being designated L; those which are closed in the right-hand position of the lever being designated R; those which are closed in either the normal or the left-hand position of the lever being designated NL; and those which are closed in either the normal or the right-hand position of the lever being designated NR.

The equipment is shown in the condition which it assumes when the track stretch is vacant, the signals 2R and 4L are at stop, and the signaling apparatus prepares the stretch for westbound traffic. At this time the contacts 20 and 21 of the traffic directional relay 2WFSR at the left-hand or west end of the stretch are in their left-hand or normal positions and connect the line wires 23 and 24 over contacts 25 and 26 of relay 2LPC to a source of energy. The relay 2LPC, not shown, is governed in the well-known manner in accordance with the aspect displayed by signal 2L and controls the polarity of the energy supplied to the line wires 23 and 24. The energy supplied to the line wires 23 and 24 feeds over front contacts of track relays 1TR, 2TR and 4TR, over back contacts 27 and 28 of relay 6RPC, and back contacts 30 and 31 of relay 6RSR to the winding of signal 6L and causes this signal, when lighted, to display its yellow or caution indication.

At this time signals 2RA and 2RB are at stop so the circuit of relay 2RRGP is complete and its contact 35 interrupts the supply of energy to terminal 15 of the C. T. C. system field station unit, and, as section 1T is vacant, contact 36 of relay 1TR is picked up and interrupts the supply of energy to terminal 19 of the field station unit. As the contacts of relay 2WFSR are in their normal position, the circuit of relay 2RHD is interrupted and its neutral contact 33 interrupts the supply of energy to relay 2RBP and its contact 101 is released and interrupts the supply of energy to terminal 14 of the field station unit. Accordingly, the indication codes sent to the office from station 1—2 release relays 1TK, 2RHK and 2RBK.

As signal 6L is conditioned to display its caution indication energy is supplied over its front contact Y to relay 6LPC and its contacts are picked up to cause energy of normal polarity to be supplied to line wires 40 and 41 leading to relay 4LHD. At this time wire 41 is connected to terminal C over front contact 42 of relay 6LPC, and wire 40 is connected over front contact 43 of relay 6LPC, winding of relay 6LAR, and back contacts G and Y of signal 6R to terminal B. The energy supplied to line wires 40 and 41 through the winding of relay 6LAR keeps its contact 45 picked up to interrupt the supply of energy to the lamp of signal 6L.

The energy supplied to line wires 40 and 41 is supplied over front contacts of track relays 5TR, 6TR and 3TR, and reverse polar contacts 50 and 51 of relay 4EFSR to the winding of relay 4LHD and picks up the relay neutral contacts and moves 65 the relay polar contacts to their left-hand or normal positions so that energy is supplied over normal polar contact 53 and neutral contact 54 to relay 4LBP and its contact 55 establishes the circuit for supplying energy to terminal 12 of the field station unit.

As shown, the contacts 58 and 59 of relay 4LHSR are in their normal positions and interrupt the circuits for supplying energy to the windings of signals 4LA and 4LB and these signals 75 are both at stop and establish the circuit of relay

4LRGP so that its contact 56 interrupts the supply of energy to terminal 13 of the field station unit. As section 3T is vacant, track relay 3TR is picked up and its contact 57 interrupts the circuit leading to terminal 10 of the field station unit. Accordingly, the indication codes sent to the office from station 3-4 release relays 3TK and 4LHK and pick up the relay 4LBK.

Referring to Fig. 2 which shows the equipment at the office, the contacts of the relay 2-4LP are in their left-hand or normal position in which they designate westbound traffic in the stretch shown in Fig. 1. At this time relay 2-4LPSR is released and its contact 62 maintains the stick circuit for relay 4LBK. As indication relays 2RHK, 4LHK, 1TK and 3TK are released and relay 4LBK is picked up, energy may be supplied to one or the other of the windings of the relay 2-4LP on movement of the signal lever 2SIG or 4SIG to thereby move the contacts of relay 2-4LP if the operator wishes to change the designated traffic direction.

If it is desired to clear one of the signals 4L, the lever 4SIG is moved to its left-hand position and the starting button 3-4STB is pressed to establish a pick-up circuit for the starting relay 3-4ST and it picks up or is actuated to establish a stick circuit for itself and to initiate operation of the office coding unit to transmit a control code to the field station at the right-hand end of the stretch. At the time the starting button 3-4STB is depressed its contact 63 is closed, but as relay 2-4LPSR is released, its contact 64 interrupts the circuit for supplying energy to relay 1-2ST and it is not actuated but remains released and does not cause a control code to be sent to the field station at the left-hand end of the stretch. This is desirable as there is no reason to send a control code to this station at this time since the stretch is assumed to be prepared for westbound traffic.

The control code transmitted as a result of picking up of relay 3-4ST causes a selector relay 3-4S to pick up with the result that the code sent to station 3-4 is determined by the condition of control circuits individual to this station. This is the case since energization of the input terminals of the office coding unit is governed by circuits including front contacts of the selector relay 3-4S, and when relay 3-4S is picked up, the selector relay 1-2S, and all other selector relays, not shown, are released. When relay 3-4S picks up terminal B of the battery is connected over normal polar contact 66 of relay 2-4LP, front contact 67 of relay 3-4S and a contact L of lever 4SIG to channel 5 and a control code is transmitted to field station 3-4 to reverse the contacts of relay 4LHSR.

When relay 3-4S picks up, its front contact 69 is closed but energy is not supplied to channel 2 as contact 66 of relay 2-4LP is in its normal position. Accordingly, the control code sent to station 3-4 maintains the contacts of relay 4EFSR in their reverse position.

On reversal of the contacts 58 and 59 of relay 4LHSR energy is supplied to the winding of signal 4LA over the circuit controlled by neutral and polar contacts of relay 4LHD and by contacts 90 and 91 which are governed in accordance with the position of switch 3W so as to establish the circuit of signal 4LA when and only when the switch is in its normal position. As shown, the switch 3W is in its normal position and the polar contacts of relay 4LHD are in their normal position so that energy is supplied to the winding of

signal 4LA to cause it to display its green or clear indication. When signal 4LA clears the circuit of relay 4LHD is interrupted and it releases to cause energy to be supplied over its back contact 56 to terminal 13 of the field station unit while a contact of relay 4LRGP momentarily interrupts the circuit of the starting relay 3-4FST to cause an indication code to be sent to the office to pick up relay 4LHK to show that signal 4LA has cleared.

When relay 4LHK picks up, it establishes a stick circuit for itself, while its contact 70 interrupts the circuits of relay 2-4LP and thereby prevents movement of the contacts of relay 2-4LP and insures that it maintains traffic in the established direction.

If a train accepts the signal and enters the stretch, the track relay 3TR will release to interrupt the circuit of relay 4LHD and contact 57 of relay 3TR establishes the circuit for supplying energy to terminal 10 of the field station, while a contact of relay 3TR interrupts the circuit of slow release relay 3TP. After release of relay 3TR and prior to release of relay 3TP, energy is supplied over back contact 72 of relay 3TR and front contact 73 of relay 3TP to the lower winding of relay 4LHSR and moves the relay contacts 58 and 59 to their normal positions in which they interrupt the circuit of signal 4LA to prevent re-clearing of signal 4LA unless the contacts of relay 4LHSR are reversed by a control code transmitted from the office.

On release of relay 4LHD its contact 53 interrupts the supply of energy to relay 4LBP and it releases to interrupt the supply of energy to terminal 12 of the field station unit, while, when signal 4LA displays its stop indication, the circuit of relay 4LRGP is complete and its contact 56 is picked up to interrupt the supply of energy to terminal 13 of the field station unit. On movement of the contacts of relays 3TR, 4LRGP and 4LBP the circuit of the starting relay 3-4FST is momentarily interrupted and its contacts are reversed to cause an indication code to be sent to the office to pick up relay 3TK and to release relays 4LHK and 4LBK. When relay 3TK picks up, its contact 75 establishes a circuit for lighting the lamp 3TKE, while, when the contacts of relay 4LBK move to their released or second position, its contact 76 establishes the circuit for lamp 2-4BKE and it is lighted to show that the block is occupied. In addition, when relay 3TK picks up, its contact 78 interrupts the circuits of relay 2-4LP, while the circuits of relay 2-4LP are also interrupted on release of contact 79 of relay 4LBK. Accordingly, the contacts of relay 2-4LP cannot be moved and this relay is certain to maintain westbound traffic in the stretch.

When the train enters the stretch and relay 3TR releases to interrupt the line wires 40 and 41, the supply of energy through the winding of relay 6LAR is cut off and its contact 45 releases to establish the circuit for the lamp of signal 6L and this signal is lighted to display the appropriate indication for the approaching train.

As the train advances into sections 6T and 5T the track relays 6TR and 5TR release to interrupt the line wires 40 and 41 and thus maintain relay 4LHD deenergized.

When the train vacates section 3T, the track relay 3TR picks up and its contact 57 interrupts the supply of energy to terminal 10 of the field station unit so that the indication code sent to the office releases relay 3TK to extinguish lamp 3TKE while contact 78 in the circuits of relay 2-4LP

is closed. At this time the contacts of relay 4LBK remain in their second or released position and its contact 79 interrupts the circuits of relay 2-4LP to prevent movement of its contacts. The relay 4LBK is effective to lock the relay 2-4LP at this time as the contacts of relays 2RBK and 2-4LPSR are released.

When the train enters section 4T, the track relay 4TR releases and energy is supplied to the relay 6LSR over the circuit which includes back contact 80 of relay 4TR and front contact 85 of relay 6LPC. Accordingly, relay 6LSR picks up and establishes a stick circuit for itself which is effective as long as either relay 4TR or relay 6LPC is released.

On release of relay 4TR the supply of energy over line wires 23 and 24 to the winding of signal 6L is cut off and the signal displays its stop indication and interrupts the circuit of relay 6LPC and it releases so that energy of reverse polarity is supplied to the line wires 40 and 41 over back contacts 43 and 42 of relay 6LPC, front contacts of relay 6LSR, winding of relay 6LAR, and back contacts G and Y of signal 6R. When the train vacates sections 6T and 5T the track relays 6TR and 5TR pick up and complete the circuit of the line wires 40 and 41 and energy is supplied to relay 4LHD to pick up its neutral contacts and move its polar contacts to their right-hand or reverse position so that, if the contacts of relay 4LHSR are reversed to clear signal 4LA, this signal will display its yellow or caution indication. As the contact 53 of relay 4LHD is in its reverse position it does not establish the circuit of relay 4LBP and it remains released and its contact 55 interrupts the circuit leading to terminal 12 of the field station unit and indication codes sent to the office do not pick up relay 4LBK.

Movement of the westbound train out of the stretch is governed by signal 2L which may be controlled from the office by the operator in any suitable manner. The details of the control of this signal are not essential to an understanding of this invention and are being omitted to simplify this disclosure.

If signal 2L is now cleared to permit the train to pass out of the single track stretch, the train may advance into section 1T so relay 1TR releases and its contact 36 establishes the circuit leading to terminal 10 of the field station unit and an indication code is sent to the office to pick up relay 1TK. When relay 1TK picks up, its contact 86 interrupts the circuits of relay 2-4LP and contact 87 of relay 1TK establishes the circuit of the lamp 1TKE.

When the train vacates the stretch so that relays 1TR, 2TR and 4TR pick up, energy is supplied over line wires 23 and 24 to the winding of signal 6L to cause it to display a permissive indication so that the circuit of relay 6LPC is established and it picks up to release relay 6LSR and to cause energy of normal polarity to be supplied to the line wires 40 and 41. This energy keeps the neutral contacts of relay 4LHD picked up and moves the polar contacts of the relay to their left-hand or normal position with the result that contacts 53 and 54 establish the circuit of relay 4LBP, and it picks up to establish the circuit for supplying energy to terminal 12 of the field station unit. Accordingly, an indication code is sent to the office which moves the contacts of relay 4LBK to their first or picked-up position to close its contacts 79 in the circuits of the relay 2-4LP and to cause contact 46 of relay 4LBK to interrupt the circuit of the lamp 2-4BKE to signal 16. At this time 4LBK has

not been cleared and section 3T is unoccupied, the indication code sent to the office at this time keeps relays 4LHK and 3TK released so their contacts in the circuits of relay 2-4LP are closed.

When the train vacates section 1T and track relay 1TR picks up, an indication code is sent to the office from field station 1-2 to release relay 1TK, thereby extinguishing lamp 1TKE and closing back contact 86 in the circuits of relay 2-4LP. Accordingly, the circuits of relay 2-4LP are now complete and energy may be supplied to one or the other of the relay windings on movement of one of the signal levers.

If the operator wishes to change traffic in the stretch from westbound to eastbound, he may do so by placing lever 4SIG in either its center position N or its right-hand position R, and moving the lever 2SIG to its position R so that energy is supplied to the upper winding of relay 2-4LP. This energy moves the relay contacts to their right-hand or reverse position with the result that energy is supplied over reverse polar contact 88 of relay 2-4LP, front contact 89 of relay 4LBK, and back contacts 90 and 91 of relays 1TK and 3TK to relay 2-4LPSR and its contacts move to their operated or picked-up position. When relay 2-4LPSR picks up, its contact 62 interrupts the stick circuit for relay 4LBK and after a short time the contacts of relay 4LBK move to their released or second position to interrupt the circuit traced above for energizing relay 2-4LPSR. However, when relay 2-4LPSR picks up, its contact 93 establishes a stick circuit including reverse polar contact 88 of relay 2-4LP, back contact 94 of relay 2RBK, and back contacts 90 and 91 of relays 1TK and 3TK, so the relay 2-4LPSR remains energized or operated after release of relay 4LBK.

When relay 2-4LPSR picks up, its contact 96 establishes a connection shunting contact 79 of relay 4LBK in the circuits of relay 2-4LP, so the operator, having secured control of relay 2-4LP, retains his control of this relay after release of relay 4LBK, and can restore the contacts of relay 2-4LP to their left-hand or normal position if he decides to restore westbound traffic in the track stretch. If, while relay 2-4LPSR is picked up, the contacts of relay 2-4LP are moved to their left-hand position, the relay 2-4LPSR will be maintained operated or energized by current supplied over the stick circuit which includes normal polar contact 88 of relay 2-4LP, front contact 97 of relay 2-4LPSR, back contact 89 of relay 4LBK, and back contacts 90 and 91 of relays 1TK and 3TK. Accordingly, contact 96 of relay 2-4LPSR maintains the connection shunting the contacts of relays 4LBK and 2RBK in the circuits of relay 2-4LP. During movement of the contact 88 of relay 2-4LP between its two positions the supply of energy to relay 2-4LPSR is interrupted, but this interruption is very brief and relay 2-4LPSR has a resistance connected across its terminals to render it slow to release so the relay contacts remain picked up and maintain the relay stick circuits during this momentary interruption of the supply of energy to the relay winding.

When relay 2-4LPSR picks up, its contact 98 interrupts the circuits of the lamps WFE, EFE and 2-4BKE, while its contacts 64 and 99 establish the circuits for the starting relays 1-2ST and 3-4ST so that both starting relays are energized or actuated if either starting button 1-2ST or 3-4ST is pressed. For purposes of illustration it will be assumed

that the contacts of relay 2-4LP are permitted to remain in their right-hand position in which they designate east-bound traffic in the stretch, that lever 2SIG is in its position R, and that starting button 1-2STB is pressed, thereby energizing relays 1-2ST and 3-4ST to cause control codes to be sent to the field stations at both ends of the stretch sequentially.

During transmission of the control code to station 1-2 energy is not supplied to channel 2 since normal polar contact 66 of relay 2-4LP is open, but energy is supplied to control channel 7 over reverse polar contact 66 of relay 2-4LP, front contact 100 of relay 1-2S, and a contact R of lever 2SIG. Accordingly, the contacts of relay 2WFSR are moved to their reverse positions, while the contacts of relay 2RHSR are also moved to their reverse positions.

When the control code is sent to station 3-4 energy is supplied to channel 2 over reverse polar contact 66 of relay 2-4LP and front contact 69 of relay 3-4S, while energy cannot be supplied to channel 5 since normal polar contact 66 of relay 2-4LP is open. Accordingly, the contacts of relay 4EFSR are moved to their left-hand or normal position, while the contacts of relay 4LHSR are maintained in their normal position.

On movement of the contacts of relay 2WFSR to their reverse position the supply of energy to line wires 23 and 24 is cut off and these wires are connected to relay 2RHD. When the supply of energy to wires 23 and 24 is cut off, the signal 6L goes to stop and interrupts the supply of energy to relay 6LPC and it releases to cut off the supply of energy to line wires 40 and 41, and to interrupt the pick-up circuit of relay 6LSR to insure that it remains released.

When the supply of energy to line wires 40 and 41 is cut off, the relay 4LHD releases, if it is not already released, because of interruption of its circuit due to movement of contacts 50 and 51 of relay 4EFSR to their normal positions. When relay 4LHD releases, its contact 54 interrupts the circuit of relay 4LBP and it releases so that its contact 55 interrupts the circuit leading to terminal 12 of the field station unit and indication codes thereafter sent from this station to the office do not pick up relay 4LBK.

When the contacts 50 and 51 of relay 4EFSR are moved to their normal position energy of one polarity or the other is supplied to line wires 40 and 41. The polarity of the energy supplied to wires 40 and 41 is governed by contacts of relay 4RPC, not shown, which is controlled in the usual manner in accordance with the indication displayed by signal 4R.

The energy supplied to line wires 40 and 41 feeds over back contacts of relays 6LPC and 6LSR to the winding of signal 6R and conditions this signal, when lighted, to display an appropriate permissive indication, while the contacts of the signal establish a circuit for relay 6RPC and it picks up to establish the circuit for supplying energy of normal polarity to line wires 23 and 24 in series with the winding of relay 6RAR. Accordingly, relay 6RAR is picked up and its contact interrupts the circuit of the lamp of signal 6R.

The energy supplied to line wires 23 and 24 is supplied over reverse polar contacts 20 and 21 of relay 2WFSR to relay 2RHD and picks up its neutral contacts and moves its polar contacts to their left-hand or normal position with the result that energy is supplied over its contacts 34 and 35 to relay 2RBP and it picks up so that its contact

tact 101 establishes the circuit leading to terminal 14 of the field station unit. As the contacts of relay 2RHSR are assumed to be reversed, energy is supplied to signal 2RA or 2RB, depending on the position of switch 1W, after energization of relay 2RHD, and when one of these signals clears the circuit of relay 2RRGP is interrupted and it releases so that its contact 35 establishes the circuit leading to terminal 15 of the field station unit.

As a result of the changes at station 1-2 the starting relay 1-2FST is reversed and an indication code is sent to the office to pick up relays 2RBK and 2RHK.

At the time the indication code from station 1-2 is received at the office, the delivery relay 1-2D picks up and a contact of relay 1-2D connects a terminal of the winding of relay 2RBK to channel 14 so that relay 2RBK is picked up by energy supplied thereto over channel 14. When the contacts of relay 2RBK move to their first or picked-up position, contact 94 interrupts the stick circuit over which energy is supplied to auxiliary relay 2-4LPSR when contact 88 of relay 2-4LP is in its reverse position so the contacts of relay 2-4LPSR move to their normal or released position after a short time interval and additionally interrupts its own stick circuits, while back contact 62 of relay 2-4LPSR is closed to provide the stick circuit for relay 2RBK after release of relay 1-2D. The operating characteristics of the C. T. C. system office equipment are such that the relay 1-2D is picked up for a period substantially longer than the release time of relay 2-4LPSR even though release of relay 2-4LPSR is delayed by the resistor connected across the terminals of the relay winding. Accordingly, when the indication code is received from station 1-2, the relay 2-4LPSR is certain to release and prepare the stick circuit for relay 2RBK before the relay 1-2D releases to interrupt the pick-up circuit for relay 2RBK.

When the contacts of relay 2RBK move to their first or pick-up position, its contact 104 interrupts the circuit of lamp 2-4BKE to prevent lighting of this lamp after release of contact 98 of relay 2-4LPSR. When the contacts of relay 2-4LPSR move to their normal or released position energy is supplied over its back contact 98 and reverse polar contact 102 to lamp EFE and it is lighted to show that the stretch has been prepared for eastbound traffic. In addition, when relay 2-4LPSR releases, its contacts 64 and 99 interrupt the circuits for the starting relays 1-2ST and 3-4ST so that each of these relays is now controlled only by its own starting button.

When relay 2-4LPSR releases, its contact 96 in the circuits of relay 2-4LP is open, but at this time contact 103 of relay 2RBK is closed and provides a connection shunting contact 96 of relay 2-4LPSR, so energy may be supplied to relay 2-4LP if the circuits of this relay are not interrupted by one of the other indication relays. Since it was assumed that one of the signals 2R was cleared and that the indication code sent to the office picked up relay 2RHK, contact 105 of relay 2RHK interrupts the circuits of relay 2-4LP and thus insures that the contacts of relay 2-4LP will remain in their right-hand position and maintain eastbound traffic in the stretch.

Because of code congestion on the C. T. C. line circuit the indication code from station 1-2 may not be sent to the office for a substantial time interval after the stretch has been prepared for eastbound traffic and one of the signals 2R gov-

erning entrance of traffic into the stretch has been cleared. Under these conditions, a train may accept the signal and enter the stretch before an indication code is sent to the office to show that the stretch has been prepared for eastbound traffic. After the train enters the stretch, the relays 2RHD and 2RBP are released so that indication codes thereafter sent to the office do not pick up relay 2RBK. However, when a train enters the stretch, relay 1TR releases and its contact 36 establishes the circuit leading to terminal 10 of the field station unit so that indication codes sent to the office pick up the relay 1TK. The relay 1TR may have associated therewith means, not shown, but well known in the art, for maintaining the supply of energy to terminal 10 of the field station after release of relay 1TR until at least one indication code is sent to the office. When relay 1TK at the office picks up, its contact 90 interrupts the circuit of the relay 2-4LPSR and its contacts move to their released or normal position to establish the circuits of the lamps 2-4BKE and EFE, and to open contact 96 of relay 2-4LPSR and thus render contact 103 of relay 2RBK effective to control the circuits of relay 2-4LP so that relay 2-4LP will maintain eastbound traffic in the stretch as long as relay 2RBK is released to indicate that the stretch is occupied.

On movement of an eastbound train through the stretch the equipment operates in substantially the same manner as during movement of a westbound train through the stretch and a detailed explanation of the operation of the equipment at such times is unnecessary.

If, while the stretch is prepared for eastbound traffic and relay 2RBK at the office is picked up, the contacts of the relay 2-4LP are moved to their left-hand position to designate westbound traffic, the relay 2-4LPSR will be picked up or operated by energy supplied over the normal polar contact 88 of relay 2-4LP and front contact 94 of relay 2RBK. As soon as relay 2-4LPSR picks up, its contact 97 establishes the stick circuit including back contact 89 of relay 4LBK, while contact 62 of relay 2-4LPSR interrupts the stick circuit for relay 2RBK so that it releases and prepares for relay 2-4LPSR the stick circuit which is effective when contact 88 of relay 2-4LP is in its reverse position. The equipment thereafter operates in substantially the same manner as during establishment of eastbound traffic and a detailed explanation of its operation is unnecessary.

As explained above, when the stretch is prepared for westbound traffic, is unoccupied, and the signals 4L are at stop, the contacts of relay 2-4LP may be moved to their right-hand position to designate eastbound traffic in the stretch. On this movement of the contacts of relay 2-4LP the relay 2-4LPSR is operated or picked up, thereby releasing relay 4LBK and establishing for itself a stick circuit governed by relay 2RBK.

After movement of the contacts of relay 2-4LP to their right-hand position, in which they designate eastbound traffic in the stretch, the wayside equipment continues to condition the stretch for westbound traffic until control codes are transmitted to the field stations at the ends of the stretch. If, after movement of the contacts of relay 2-4LP to their right-hand position, the operator does not press one of the starting buttons for a time interval, an indication code may be sent from station 3-4 to the office. This indication code will cause relay 4LBK to pick up during the picked up time of delivery relay 3-4D. 70

However, picking up of relay 4LBK does not release relay 2-4LPSR since relay 2-4LPSR is energized by current supplied over the stick circuit which includes reverse polar contact 88 of relay 2-4LP, its own front contact 93 and back contact 94 of relay 2RBK. Accordingly, relay 2-4LPSR remains picked up and interrupts the stick circuit for relay 4LBK so that on release of the delivery relay 3-4D the relay 4LBK also releases, while the relay 2-4LPSR maintains the circuits for the starting relays and for relay 2-4LP, and interrupts the circuits of the lamps 2-4BKE, EFE and WFE.

If a starting button is now pressed, control codes will be sent to the stations at both ends of the stretch and the wayside equipment will prepare the stretch for eastbound traffic and the equipment will thereafter function as explained above.

The equipment operates in a similar manner if, while the wayside equipment prepares the stretch for eastbound traffic, the contacts of relay 2-4LP are moved to their left-hand position in which they designate westbound traffic in the stretch, but pressing of a starting button is delayed so an indication code is sent from station 1-2 to the office and picks up relay 2RBK. When the contacts of relay 2-4LP are in their left-hand position, the relay 2-4LPSR is energized by current supplied over the stick circuit which includes normal polar contact 88 of relay 2-4LP, its own front contact 97, and back contact 89 of relay 4LBK. As relay 2-4LPSR is energized by current supplied over a circuit independent of relay 2RBK, the relay 2-4LPSR is not affected by picking up of relay 2RBK, and remains picked up and interrupts the stick circuit for relay 2RBK.

It may happen that after control codes are sent to change the direction of traffic in the stretch, but before an indication code has been sent to the office to show that the new direction of traffic has been established, the operator may decide to restore the original direction of traffic and for this purpose he will return the contacts of relay 2-4LP to their original position, and he may not press a starting button for some time thereafter. For purposes of illustration, assume that the stretch is prepared for westbound traffic, that relay 2-4LP is operated to designate eastbound traffic in the stretch and that control codes are transmitted for this purpose. The operator may now move the contacts of relay 2-4LP to their normal or left-hand position to again designate westbound traffic, but may not press the starting button immediately. After the wayside equipment responds to the control codes and prepares the stretch for eastbound traffic, an indication code may be sent to the office to pick up relay 2RBK, but this will not release relay 2-4LPSR since after movement of the contacts of relay 2-4LP to their normal position the relay 2-4LPSR is energized by current supplied over the stick circuit controlled by relay 4LBK and is not affected by relay 2RBK.

The equipment operates in a similar manner if, after transmission of control codes to prepare the stretch for westbound traffic, the contacts of relay 2-4LP are returned to their right-hand position to designate eastbound traffic and control codes are not transmitted for a short interval.

From the foregoing it will be seen that the auxiliary relay 2-4LPSR is picked up or operated on movement of the contacts of relay 2-4LP, and when picked up or operated remains picked up until an indication code is received which shows

that traffic has been established in the direction designated by the relay 2-4LP. This insures that, until traffic is established in the designated direction, the relay 2-4LPSR will maintain the circuits for the starting relays and cause control codes to be sent to both ends of the stretch when the starting button for the station at either end of the stretch is pressed. This insures that the equipment will operate promptly and positively to prepare the stretch for traffic in the direction designated by relay 2-4LP, while it also insures that relay 2-4LPSR will maintain the circuits for relay 2-4LP until preparation of the stretch for traffic has been completed.

In addition, it will be seen that if following a change in the designated traffic direction a train enters the stretch before an indication code can be sent to the office, the occupied detector section indication code which is thereafter sent to the office will release the auxiliary relay 2-4LPSR and thereby cause the block indication relays to control the relay 2-4LP so that the designated traffic direction cannot be changed during occupancy of the stretch.

Although the invention has been illustrated and described in connection with a stretch of track equipped with wayside signaling apparatus governed over line wires, the invention is also applicable to stretches equipped with other forms of wayside signaling apparatus, such, for example, as coded track circuit signaling equipment.

Although I have illustrated and described one form of railway signaling apparatus embodying my invention, it should be understood that various changes and modifications may be made therein within the scope of the appended claims without departing from the spirit and scope of my invention.

Having thus described my invention, what I claim is:

1. In a system of centralized traffic control for a stretch of single track railroad between the ends of adjacent passing sidings, electroresponsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing entrance of traffic into said stretch in accordance with traffic conditions in the stretch, means at the ends of said stretch governed through said code communication system in accordance with the condition of said electroresponsive means for conditioning said system of reversible circuits to prepare the stretch for one direction of traffic or the other and to also control the transmission of block indication codes from one field station only for one direction of traffic and from the other field station only for the other direction of traffic which show when the entire stretch is unoccupied, a block indication relay at the office for each end of said stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative

10
0 after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, circuit means for moving the contacts of said auxiliary relay to their operated position when said electroresponsive means is operated to change the designated direction of traffic, means for moving the contacts of said auxiliary relay to their normal position when the block indication relay which shows traffic conditions in the stretch for the traffic direction designated by said electroresponsive means responds to an unoccupied indication code, and means for operating said electroresponsive means to change the designated direction of traffic only when the contacts of one of said block indication relays are in their first position or the contacts of said auxiliary relay are in their operated position.

2. In a system of centralized traffic control for a stretch of single track railroad between the ends of adjacent passing sidings, manually controlled electroresponsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission of block indication codes from one field station only for one direction of traffic and from the other field station only for the other direction of traffic which show when the entire stretch is unoccupied, a block indication relay at the office for each end of said stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, circuit means for moving the contacts of said auxiliary relay to their operated position when said electroresponsive means is operated to change the designated direction of traffic, means for moving the contacts of said auxiliary relay to their normal position when the block indication relay which shows traffic conditions in the stretch for the traffic direction designated by said electroresponsive means responds to an unoccupied in-

dication code, a starting relay at the office for each end of the stretch adapted when actuated to initiate transmission of a control code to the field station at the associated end of the stretch, and a starting button for each starting relay, each starting button controlling a circuit for actuating the associated starting relay and also controlling a circuit for actuating the starting relay for the other end of the stretch provided the contacts of said auxiliary relay are in their operated position.

3. In a system of centralized traffic control for a stretch of single track railroad between the ends of adjacent passing sidings, manually controlled electro-responsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission of block indication codes from one field station only for one direction of traffic and from the other field station only for the other direction of traffic which show when the entire stretch is unoccupied, a block indication relay at the office for each end of said stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, circuit means for moving the contacts of said auxiliary relay to their operated position when said electroresponsive means is operated to change the designated direction of traffic, means for moving the contacts of said auxiliary relay to their normal position when the block indication relay which shows traffic conditions in the stretch for the traffic direction designated by said electroresponsive means responds to an unoccupied indication code, and means governed by said electroresponsive means for indicating the designated direction of traffic in said stretch provided the contacts of said auxiliary relay occupy their normal position.

4. In a system of centralized traffic control for a stretch of single track railroad between the ends of adjacent passing sidings, electroresponsive means at a remote control office for designating the direction of traffic in said stretch, an auxiliary relay at said office having contacts

which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission of block indication codes from one field station only for one direction of traffic and from the other field station only for the other direction of traffic which show when the entire stretch is unoccupied, a block indication relay at the office for each end of said stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, circuit means for moving the contacts of said auxiliary relay to their operated position when said electroresponsive means is operated to change the designated direction of traffic, means for moving the contacts of said auxiliary relay to their normal position when the block indication relay which shows traffic conditions in the stretch for the traffic direction designated by said electroresponsive means responds to an unoccupied indication code, and means for operating said electroresponsive means to change the designated direction of traffic only when the contacts of one of said block indication relays are in their first position or the contacts of said auxiliary relay are in their operated position.

5. In a system of centralized traffic control for a stretch of single track railroad between the ends of adjacent passing sidings, electroresponsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission of block indication codes from one field station only for one direction

tion of traffic and from the other field station only for the other direction of traffic which show when the entire stretch is unoccupied, a block indication relay at the office for each end of said stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, circuit means for moving the contacts of said auxiliary relay to their operated position when said electroresponsive means is operated to change the designated direction of traffic, means for moving the contacts of said auxiliary relay to their normal position when the block indication relay which shows traffic conditions in the stretch for the traffic direction designated by said electroresponsive means responds to an unoccupied indication code, means for operating said electroresponsive means to change the designated direction of traffic only when the contacts of one of said block indication relays are in their first position or the contacts of said auxiliary relay are in their operated position, a starting relay at the office for each end of the stretch adapted when actuated to initiate transmission of a control code to the field station at the associated end of the stretch, and a starting button for each starting relay, each starting button controlling a circuit for actuating the associated starting relay and also controlling a circuit for actuating the starting relay for the other end of the stretch provided the contacts of said auxiliary relay are in their operated position.

6. In a system of centralized traffic control for a stretch of single track railroad between the ends of adjacent passing sidings, manually controlled electroresponsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission of block indication codes from one field station only for one direction of traffic and from the other field station only for the other direction of traffic which show when the entire stretch is unoccupied, a block indication relay at the office for each end of said stretch governed by the block indication codes transmitted from the field sta-

tion at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, circuit means for moving the contacts of said auxiliary relay to their operated position when said electroresponsive means is operated to change the designated direction of traffic, means for moving the contacts of said auxiliary relay to their normal position when the block indication relay which shows traffic conditions in the stretch for the traffic direction designated by said electroresponsive means responds to an unoccupied indication code, and means governed by said block indication relays provided the contacts of said auxiliary relay are in their normal position for indicating the occupied condition of said stretch.

7. In a system of centralized traffic control for a stretch of single track railroad between the ends of adjacent passing sidings, electroresponsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission of block indication codes from one field station only for one direction of traffic and from the other field station only for the other direction of traffic which show when the entire stretch is unoccupied, a detector section at each end of the stretch including the track switch for connecting the track stretch with the adjacent passing siding, each detector section being provided with a track circuit including a track relay, a block indication relay at the office for each end of said stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication

relay contacts to move to their second position on movement of the auxiliary relay contacts to their operated position, a detector section indication relay at said office for each of said detector sections, each of said detector section indication relays being governed by the track relay for the corresponding detector section through said code communication system, circuit means for moving the contacts of said auxiliary relay to their operated position when said electroresponsive means is operated to change the designated direction of traffic, means for moving the contacts of said auxiliary relay to their normal position when a detector section indication relay responds to an occupied indication code or when the block indication relay which shows traffic conditions in the stretch for the traffic direction designated by said electroresponsive means responds to an unoccupied indication code, and manually controlled means for operating said electroresponsive means to change the designated direction of traffic provided the contacts of one of said block indication relays occupy their first position or the contacts of said auxiliary relay are in their operated position.

8. In a system of centralized traffic control for a stretch of single track railroad between the ends of adjacent passing sidings, manually controlled electroresponsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission of block indication codes from one field station only for one direction of traffic and from the other field station only for the other direction of traffic which show when the entire stretch is unoccupied, a detector section at each end of the stretch including the track switch for connecting the track stretch with the adjacent passing siding, each detector section being provided with a track circuit including a track relay, a block indication relay at the office for each end of said stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, a detector section indication relay

at said office for each of said detector sections, each of said detector section indication relays being governed by the track relay for the corresponding detector section through said code communication system, circuit means for moving the contacts of said auxiliary relay to their operated position when said electroresponsive means is operated to change the designated direction of traffic, means for moving the contacts of said auxiliary relay to their normal position when a detector section indication relay responds to an occupied indication code or when the block indication relay which shows traffic conditions in the stretch for the traffic direction designated by said electroresponsive means responds to an unoccupied indication code, and means governed by said electroresponsive means for indicating the designated direction of traffic provided the contacts of said auxiliary relay occupy their normal position.

9. In a system of centralized traffic control for a stretch of single track railroad between the ends of adjacent passing sidings, manually controlled electroresponsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system or reversible circuits to prepare the stretch for one direction of traffic or the other and to also control the transmission of block indication codes from one field station only for one direction of traffic and from the other field station only for the other direction of traffic which show when the entire stretch is unoccupied, a detector section at each end of the stretch including the track switch for connecting the track stretch with the adjacent passing siding, each detector section being provided with a track circuit including a track relay, a block indication relay at the office for each end of said stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, a detector section indication relay at said office for each of said detector sections, each of said detector section indication relays being governed by the track relay for the corresponding detector section through said code communication system, circuit means for moving the contacts of said auxiliary relay to their operated position when said electroresponsive means is operated to change the designated direction of traffic, means for moving the contacts of said auxiliary relay to their normal position when a detector section indication relay responds to an occupied indication code or when the block indication relay which shows traffic conditions in the stretch for the traffic direction designated by said electroresponsive means responds to an unoccupied indication code, and means governed by said electroresponsive means for indicating the designated direction of traffic provided the contacts of said auxiliary relay occupy their normal position.

tacts of said auxiliary relay to their operated position when said electroresponsive means is operated to change the designated direction of traffic, means for moving the contacts of said auxiliary relay to their normal position when a detector section indication relay responds to an occupied indication code or when the block indication relay which shows traffic conditions in the stretch for the traffic direction designated by said electroresponsive means responds to an unoccupied indication code, and means governed by said block indication relays provided the contacts of said auxiliary relay are in their normal position for indicating the occupied condition of said stretch.

10. In a system of centralized traffic control for a stretch of single track railroad between the ends of adjacent passing sidings, electroresponsive means at a remote control office for designating the direction of traffic in said stretch, an auxiliary relay at said office having contacts which have a normal and an operated position, a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission from the field station at the entrance end of the stretch of block indication codes which show when the entire stretch is unoccupied, a block indication relay at the office for each end of the stretch governed by the block indication codes transmitted from the field station at the corresponding end of the stretch, the contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, circuit means for moving the contacts of said auxiliary relay to their operated position when said electroresponsive means is operated to change the designated direction of traffic, means for moving the contacts of said auxiliary relay to their normal position when the block indication relay for the end of the stretch designated the entrance end by said electroresponsive means responds to an unoccupied indication code, and manually controlled means for operating said electroresponsive means to change the designated traffic direction provided the contacts of one of said block indication relays occupy their first

position or the contacts of said auxiliary relay occupy their operated position.

11. In a system of centralized traffic control for a stretch of single track railroad between the ends of adjacent passing sidings, electroresponsive means at a remote control office for designating the direction of traffic in said stretch, an auxiliary relay at said office having contacts which have a normal and an operated position, 5 a code communication system including a field station at each end of said stretch connected with said office, a system of reversible circuits extending the length of said stretch for controlling signals governing train movement into and through said stretch in one direction or the other in accordance with traffic conditions in said stretch, means at the ends of said stretch governed through said code communication system in accordance with the condition of said electroresponsive means for conditioning said system of reversible circuits to prepare the stretch for one direction of traffic or the other and to also control the transmission from the field station at the entrance end of the stretch of block indication codes which show when the entire stretch is unoccupied, a block indication relay at the office for each end of the stretch governed by the block indication codes transmitted from the field station at the corresponding end of the stretch, the 20 contacts of each block indication relay being moved to their first or their second position during receipt of an indication code according as the indication code does or does not show that the stretch is unoccupied, means for each of said block indication relays effective during the intervals between receipt of indication codes for controlling said relay and operative after movement of the relay contacts to their first position to cause the relay contacts to remain in their first position as long as the contacts of said auxiliary relay remain in their normal position and to cause the block indication relay contacts to move to their second position on movement of the auxiliary relay contacts to their operated position, circuit means for moving the contacts of said auxiliary relay to their operated position when said electroresponsive means is operated to change the designated direction of traffic, means for moving the contacts of said auxiliary relay to their normal position when the block indication relay for the end of the stretch designated the entrance end by said electroresponsive means responds to an unoccupied indication code, manually controlled means for operating 25 said electroresponsive means to change the designated traffic direction provided the contacts of one of said block indication relays occupy their first position or the contacts of said auxiliary relay occupy their operated position, a starting relay at the office for each end of the stretch adapted when actuated to initiate transmission of a control code to the field station at the associated end of the stretch, and a starting button for each starting relay, each starting button controlling a circuit for actuating the associated starting relay and also controlling a circuit for actuating the starting relay for the other end of the stretch provided the contacts of said auxiliary relay are in their operated position.
